WALTER A. BOCKIUS, OF WILMETTE, AND HOWARD B. JONES, OF EVANSTON, ILLINOIS

MOUNTING FOR CONNECTING DEVICES

Application filed March 11, 1929. Serial No. 346,123.

Our invention relates to a mounting for connectors, and more particularly to means for securing connector blocks such as are used in the wiring connections for a radio set in a wall of the radio cabinet.

It is the principal purpose of this invention to provide a device of this character by the use of which the connecting blocks may be fastened securely to a wall without the necessity of using screws and by the mere punching of a hole in the wall of the proper size to receive the connecting block.

It is also a purpose of this invention to provide a device of this character in which, whenever it is necessary to do so, the connecting block may be detached from the casing upon which it is secured, for purposes of repair.

Other objects and advantages of the invention will appear as the description proceeds, in connection with the accompanying drawings, wherein the preferred form of the invention is shown. It is obvious, however, that various modifications may be made from the exact details shown and described, and it is to be understood that I intend to avail myself of all such modifications as will occur to one skilled in this art and as fall within the scope of the claims.

In the drawings,

Fig. 1 is a plan view of a portion of a wall, such as the wall of a radio cabinet, with a connecting block mounted thereon;

Fig. 2 is a section on the line 2—2 of Fig. 1; and

Fig. 3 is a section taken through the casing, showing the connecting block partially inserted in the holding means.

Referring now in detail to the drawings, there is shown at 5 a portion of a wall, which may be the wall of a radio cabinet or power unit case, and which wall, as is common in present practice, is constructed of a relatively thin metal construction. The material of the wall, however, is not important to the present invention, as our improved securing means is applicable equally well to various types of casings.

The wall, as shown, is cut out to provide a rectangular aperture 6 conforming in

shape to the top 7 of the socket portion of the connecting block. This connecting block, as shown, has longitudinal ridges 8 and 9 extending lengthwise thereof at a short distance below the top 7. This connecting block, of course, has terminals, as indicated at 10 and 11, for connection to the electrical apparatus within the casing, and co-operates with the plug portion 12, having terminals such as indicated at 13 and 14 therein. The details of this connecting plug form a separate application filed March 11, 1929, by Howard B. Jones, and bearing Serial No. 346,005.

Now the means for securing the socket portion of the connecting block to the wall 5 consists of a pair of elongated spring members 15 and 16, which are substantially the length of the aperture provided at 6 in the wall 5. These spring members 15 and 16 are bent, as shown at 17 and 18, to form grooves fitting over opposite edges of the aperture 6. The spring members are then curved downwardly and inwardly, as shown clearly at 19 and 20, and are provided with the upturned edges 21 and 22 which press against the lower edges of the ridges 8 and 9, as shown more clearly in Fig. 3. At the opposite ends of the members 15 and 16, these edges 21 and 22 may be cut away slightly so as to facilitate the insertion of the block therebetween, but this, of course, is not necessary in all cases.

Now, in mounting the block in position, the members 15 and 16 are first fitted in position, as shown in Fig. 3, and then the block is inserted between them at one end so that the edges 21 and 22 engage the undersides of the ridges 8 and 9 and tend to press the block upwardly against the wall 5. The block is then pressed along beneath the wall by sliding it relative to the members 15 and 16 until it aligns with the opening 6, and, when the block is in suitable alignment with the opening 6, the resiliency of the members 15 and 16 will force the block upwardly into the position shown in Fig. 2, so that the portion 7 thereof is substantially flush with the tops of the bent portions 17 and 18 on the members 15 and 16.

The block is now mounted in position for permanent use, since it cannot slide endwise due to the projection of the portion 7 upwardly into the opening 6, and the spring members 15 and 16 prevent it from dropping. 5 The plug portion 12 of the connector may then be inserted in or separated from the socket portion when desired, and if it becomes necessary to repair the socket portion 10 for any reason, this portion may be readily removed by pressing the same downwardly with sufficient pressure to move the top of the portion 7 below the level of the wall 5 and then sliding the block endwise out of engagement with the spring members 15 and 16. 15

From the above description, it is thought that the construction and advantages of this device will be clear to those skilled in this art, and having thus described our invention, 20 what we claim as new and desire to secure by Letters Patent is:

1. In a device of the character described, a wall having a rectangular aperture therein, a connecting block having a reduced face portion 25 adapted to fit in said aperture, spring clips secured along two opposite side edges of said aperture and cooperating means on said clips and block slidably engaging whereby said block may be slid between said clips into 30 alignment with said aperture and then snapped into position with said portion extending into said aperture.

2. In a device of the character described, a wall having a rectangular aperture therein, 35 a connecting block having a reduced face portion adapted to fit in said aperture, spring clips secured along two opposite side edges of said aperture and cooperating means on said clips and block slidably engaging whereby said block may be slid between said clips into 40 alignment with said aperture and then snapped into position with said portion extending into said aperture, said means comprising curved portions on said clips terminating in inwardly and upwardly directed substantially parallel edges, and shoulders on 45 said block with which said edges slidably engage.

3. In a device of the character described, a wall having a rectangular aperture therein, a connecting block having a reduced face portion 50 adapted to fit in said aperture, spring clips secured along two opposite side edges of said aperture and cooperating means on said clips and block slidably engaging whereby said block may be slid between said clips into 55 alignment with said aperture and then snapped into position with said portion extending into said aperture, said clips being bent to provide longitudinal grooves detachably receiving the edges of said wall at said aperture for securing the clips thereon.

4. In a device of the character described, a wall having a rectangular aperture therein, a 60 connecting block having a reduced face por-

tion adapted to fit in said aperture, spring clips secured along two opposite side edges of said aperture and cooperating means on said clips and block slidably engaging whereby said block may be slid between said clips into 65 alignment with said aperture and then snapped into position with said portion extending into said aperture, each of said clips being formed of single piece of metal curved to provide a groove along one longitudinal edge and to provide a wide opening on the opposite side of the material from said groove between said groove and the other edge. 70

In witness whereof, we hereunto subscribe 80 our names this 5th day of February A. D., 1929.

WALTER A. BOCKIUS.
HOWARD B. JONES.
